DESIGN FOR AN ADVERTISING FIGURINE

Emerson C. Bishop, Los Angeles, Calif.

Application April 18, 1947, Serial No. 138,473

Term of patent 14 years

(Cl. D1—3)

To all whom it may concern:

Be it known that I, Emerson C. Bishop, a citizen of the United States, residing at Los Angeles, in the county of Los Angeles and State of California, have invented a new, original, and ornamental Design for an Advertising Figurine, of which the following is a specification, reference being had to the accompanying drawing, forming a part thereof.

In the accompanying drawing:

Fig. 1 is a front elevational view of an advertising figurine, showing my new design;

Fig. 2 is a side elevational view of the advertising figurine, and

Fig. 3 is a rear elevational view of the advertising figurine.

I claim:

The ornamental design for an advertising figurine, as shown.

EMERSON C. BISHOP.
